Samuel W. Phelps, of City of Cincinnati State of Ohio.

Letters Patent.

Aug 18 '42

The Schedule referred to in these Letters Patent, and making part of the same containing a description in the words of the said Samuel W. Phelps, himself of his improvement in cooking stoves, called Phelps' Patent ^{cooking} ~~cooking~~ ~~stove~~ ~~stove~~

To all persons to whom these presents shall come,

Be it known that I Samuel W. Phelps, of the city of Cincinnati in the County of Hamilton and State of Ohio, have invented, constructed, made, and applied to use a new and useful improvement in cooking stoves, called "Phelps' Patent ^{cooking} ~~cooking~~ ~~stove~~ ~~stove~~ ~~stove~~" specified in the words following, to wit.

The said stoves are intended for steam boats, hotels &c. and vary in size to suit circumstances, they are made of wrought or cast iron, the second size is large enough to seat for forty eight to one hundred persons, it is three feet long two feet high, and two feet wide, one of the broad sides is the front of the stove, and presents to view the fire place, the air chamber, the oven, and the ash pit. The boilers are placed upon the top of the stove, and drop into it from one and a quarter, to the and a half inch. The flue from the furnace extends beneath the boilers, and over the top of the oven, thence down the side of the oven, farthest from the furnace, thence beneath the bottom of the oven, thence against the back of it, thence into the pipe. So that the oven is heated on every side except the front. The bottom plate of the oven, and the back plate, are made of fire bed iron, supported by cast iron frames or otherwise. The advantage of this is, that the bottom and back of the oven, being subject to less heat than the sides near the furnace, may be thinner than those sides, and thus all sides get equally heated in the same time. The bottom portion of the flue beneath the oven, is divided by a partition commencing at its right hand side, back, and running diagonally forward, to within nine inches of the front, the object of which is to carry the hot-
air flame & air forward, and spread it well over the bottom of the oven before it reaches to the back plate.

The advantage of having the flue pass out of the back of the stove, and not at

of the lime solution. The first column about 10 inches was dug up, took the whole depth of the lime
the first column was broken at the bottom of the stone. The rock
immediately above this place the lime on the bottom plate of the lime below
the first part of the stone, very irregular with the tree 6 inches deep. I
only one and 1/2 the long. About 6 inches the whole part of the stone, and is
one of the thick trees.

Between the furnace and oven there is a chamber of the height of the oven
the height of it, and one and a quarter inch wide in the clear. There are three
holes wholly in the back or bottom of the oven top to admit cold air, three similar
holes in the front oven heat from the air top to the oven, and three similar
holes to let the air pass from out of the oven into the flue, and these similar
holes are of the size of three holes mentioned above, and if properly applied to
the air current of heated air, if necessary, will be the top of this air
current to equalize the heat of the oven, prevent the furnace from
burning one side first before the other, and create a current of fresh air
through the oven, preventing the amalgamation of the ash of the meat
The top can be seen that mentioned I have found by experience to
be the best. The various dimensions spoken of in this specification
will not be lost accountants.

claims on the above specification the following improvement, as being both an
expansion of the plan given in it, and, out of the lack of the same, whereby the
gas pipes are heated, and soon as left at the side of the furnace
are heated, & the bottom part back of the furnace are made thin
so that the gas may travel in proportion to their distance from the source of
heat, and they will rise of their own accord equally heated at a nearly

the same time. 3° The air chamber, interposed between the furnace & the oven
4° The convenient combination of these advantages, in the most condensed and
simple form for the use of steam boats, and hotels, &c.

In testimony that the above is a true specification of my said
improvement I have hereunto set my hand and seal, this 7th day of July 1834.

Witness,

Thos. Wright,

Isiah Forbes
